SOCKET FOR LIGHT TUBES

Thomas A. Carter, Jr., Grand Rapids, Mich., assignor to Grand Rapids Store Equipment Company, Grand Rapids, Mich., a corporation of Michigan

Application April 17, 1939, Serial No. 268,251

5 Claims. (Cl. 173—328)

This invention relates to light sockets which, preferably, are used in pairs, one of the sockets spaced from the other, and between which a tubular lighting bulb is disposed, being detachably held at each end in a socket. The sockets are particularly useful in connection with fluorescent lighting tubes.

This invention is more particularly directed to sockets for detachably holding the opposite ends of a fluorescent lighting tube within a reflector, the tube being located within a reflector which is generally of a trough shape and near the bottom of the trough. With this construction the tube may be readily connected with the sockets which carry the same, but the disconnection thereof from the sockets is hampered because of the position of the tube within the reflector. My invention includes as a part thereof a very simple, yet effective means for detaching the tube independently at each end from the sockets which carry it, one at each end of the tube.

An understanding of the invention may be had from the following description, taken in connection with the accompanying drawings, in which:

Fig. 1 is a fragmentary perspective view showing a fluorescent lighting tube mounted within a reflector by means of the sockets of my invention.

Fig. 2 is a fragmentary longitudinal section through the reflector and side elevation of the lighting tube and the sockets which carry it.

Fig. 3 is a transverse section through the tube and reflector.

Fig. 4 is an enlarged perspective view of a socket made in accordance with my invention.

Fig. 5 is an end elevation thereof.

Fig. 6 is a transverse section through the socket on a plane a short distance back of the front of the socket, shown in Fig. 5.

Fig. 7 is a vertical section substantially on the plane of line 7—7 of Fig. 6, looking in the directions indicated by the arrows.

Fig. 8 is a substantially central longitudinal vertical section through the socket.

Fig. 9 is an under plan view thereof, and

Fig. 10 is a perspective view of one of the spring tube retaining contacts, two of which are used in each socket construction.

Like reference characters refer to like parts in the different figures of the drawings.

The reflector 1 generally of a channel shape in cross section, is of any desired length, whereby it may carry and support one or more of the fluorescent lighting tubes. Between the sides of the reflector and adjacent the bottom thereof is

a flat plate 2 extending lengthwise of the reflector and having a flange at one side through which screws 3 may be inserted for securing the plate in position within the reflector; and of course the screws, if desired, may be thence driven into an upper rail of a show case for securing the reflector in horizontal position with its open side directed interiorly into the show case. Between the bottom of the reflector and said plate the wiring for the lights is concealed.

The tubular fluorescent lighting tube is carried at each end by a socket of my invention. The socket includes a body 4 which at one end has a projecting portion 5. This body is of a suitable electro non-conducting or insulating material such as Bakelite, porcelain or any other suitable material. At its lower side and adjacent one end is a projecting transverse rib 6, spaced from which is a shorter projecting rib 7, the two having between them a connecting rib 8 (Fig. 4), all integral with the body of the socket. To a side of the rib 7 is a threaded opening 9 into which a screw 10 may be screwed after passing through the plate 2, as in Fig. 7. The plate 2 will be provided with a suitable opening through which the ribs 6 and 7 may extend, as in Figs. 7 and 8, to locate and hold the socket in place on the plate in connection with the securing screw 10.

Two contacting and holding members, each made from sheet metal, are provided. At one end is a substantially square base 11 with a section 12 turned therefrom at right angles, from which at one end an arm 13 projects for a distance, integral with the section 12 and bent to lie at an acute angle to the plane thereof. At the free end of the arm 13 is an arm 14 extending at right angles, the free portion of which is bent angularly as at 15, thence back again at 16, and then again in the same direction as the part 15, as at 17, the part 17 furnishing a terminal lip for the contact. The body of the socket is provided with suitable grooves and upwardly extending passages 18, back of what may be called the front face of the socket, which passages at their outer portions join with slots 19, one at either side of the central longitudinal plane of the socket, shown in Fig. 5; and beyond the bottoms of which slots 19, the terminal lips 17 and the annular portions 16 connected therewith extend. Metal sleeves 21 are molded and permanently secured into the body 4 and are shouldered at their outer ends and pass through holes in the contact members 11 and are riveted to retain the contact members in place and receive the screws 20. The wires 23 which carry electric current

are bared by removing the insulation at the proper points in the length thereof, and such bared portions are clamped between the heads of the screws 20 and the base members 11 of the contacts.

Centrally of and a short distance back of the front face of the body a passage is made for a rod 24, which at one end has an outwardly projecting foot 25, there being a slot 25a in the body 10 whereby the rod 24 may be moved longitudinally a short distance by grasping the outer head or knob 26 thereof. In its innermost position the foot 25 comes to the plate 2, as in Fig. 8.

The fluorescent lighting tube 27 is of the regular and normal construction, having metallic caps 28, one at each end, from each of which two pins 29 extend outward. The slots 19 are so located that the pins 29 may enter and move lengthwise thereof, engaging against the terminal 20 lip portion 17 to spring the free end portions of the contacts to one side until the corners where the parts 16 and 17 join together are passed, whereupon the pins 29 reach the bottoms of the slots 19 and are yieldingly retained by the sections 16 coming partially thereover, as shown in Fig. 5. The lighting tubes may be very readily applied to the sockets by merely putting said end pins 29 in the slots 19 and pushing them inwardly until the bottoms of the slots 19 are reached. 25 30 whereupon the free ends of the sheet metal contacts serve as yielding keepers to hold the tube in and between the two sockets carrying the same.

When thus located the tube at its sides is relatively close to the adjacent portions of the reflector so that it is not easy to grasp the tube itself to remove it. But by an outward pull upon the heads 26 of the rods 24, the foot members 25 engage against the ends 28 of the light tube and 35 40 cause the pins 29 to move outwardly in the slots 19, disengaging from the contacts which yield upon the application of relatively light pulling force upon the rods 24.

The construction described is very practical, 45 useful and effective. With it the elongated lighting tubes may be readily attached in place for use, and may be removed for replacement whenever necessary in a particularly simple manner.

The invention is defined in the appended claims, 50 and is to be considered comprehensive of all forms of structure coming within the scope of said claims.

I claim:

1. A lighting socket of the class described comprising, a body, slots in one face of said body to receive contact pins on a lamp, contact means in said slots to releasably hold the lamp therein, and a manually accessible substantially L-shaped pin slidably mounted in said body and movable longitudinally of said slots having one arm ad-

jacent an end of the lamp for ejecting said lamp therefrom.

2. A lighting socket of the class described comprising, a body, slots in one face thereof to receive contact pins on a lamp, contact means to 5 releasably hold a lamp in said slots, and a rod slidably mounted in said body longitudinally of said slots having one end extending therebeyond and a lateral projection on the other end of said rod extending beyond said body adjacent an end 10 of the lamp whereby a sliding movement of said rod will eject the lamp from the socket by means of said projection.

3. A lighting socket of the class described comprising, a body having a base side, a flat face 15 perpendicular thereto, said body having slots at said face extending inwardly into said body and from the outer part of the body for a distance toward the base side of the socket, passages communicating with said slots and reaching said 20 base, keepers in said body to engage pins entering said slots, other slots having said keepers therein, and a rod slidably mounted on said body a short distance within the flat face thereof and between the last named slots, said rod at its inner end having an outwardly extending projection, and the body for a short distance outwardly from said projection being slotted, whereby the 25 rod and said projection may be drawn outwardly a limited distance. 30

4. A lighting socket adapted to receive a pair of pins projecting from an end of a fluorescent lighting tube comprising, a body having slots at a face thereof for the reception of said pins, spring actuated keeper contacts mounted on and 35 within the body, each having a free end portion extending into a slot over which the pins may ride to reach the inner closed ends of the slots and be yieldingly retained by said keeper contacts after having reached the inner ends of said 40 slots, and elongated means mounted on the socket adapted to be manually moved longitudinal in a straight line outwardly, said means having a projection at its inner end to engage against a tube and move the pins thereon outwardly to dis- 45 engage them from said keeper contacts.

5. A socket for light tubes comprising, a body having a front face, slots in said face open at their outer ends adapted to receive pins on the end of the tube, spring retaining contacts 50 mounted within said body to engage with the pins when they are moved inwardly to the inner ends of the slots, and a manually accessible slidable rod mounted on said body having a lateral projection at its inner end located adjacent an end 55 of the tube, whereby on outward movement of the rod the pins on the end of the tube may be disengaged from said contacts, as specified.
